UNITED STATES PATENT OFFICE.

JOSEPH ARTHUR JONES, OF LOZELLS, BIRMINGHAM, ENGLAND.

CONVERTIBLE TABLE FOR TYPE-WRITERS OR THE LIKE.

1,295,326.

Specification of Letters Patent. Patented Feb. 25, 1919.

Application filed October 30, 1917. Serial No. 199,320½.

To all whom it may concern:

Be it known that I, JOSEPH ARTHUR JONES, subject of the King of Great Britain, residing at 8 Carlyle road, Lozells, Birmingham, England, have invented certain new and useful Improvements in Convertible Tables for Type-Writers or the like, of which the following is a specification.

10 The invention comprises an improved convertible table for typewriters and the like of the type in which a cover or lid may hinge or slide from its closing position, *e. g.*, horizontal into a vertical position when open, and in such movement may raise a shelf or support for a typewriter or the like into the desk opening so as to be in a position for use.

20 My invention has for its object to provide a simple and effective construction. In accordance with the invention in combination with cabinet sides and a back portion, I employ a shelf sliding upon a support at its front end and with pins or projections at or near the rear end working in a groove or slot in the sides, and a top pivoted by means of cranks or arms and connected to the shelf by cables, chains or like means so that the two work in the desired relation.

30 On the drawings:—

Figure 1 is a front view of the table in the closed position.

Fig. 2 is a similar view open.

35 Fig. 3 is a plan of Fig. 2.

Fig. 4 is a section on line 4—4 of Fig. 3 showing a typewriter in dotted lines on its shelf or support.

40 Fig. 5 is a similar view to Fig. 4 but showing the machine inclosed and the cover in position to form a flat table top.

In the improved table a cabinet frame, with two sides *a*, a back *b* and a portion of a top *c* is provided, and a shelf *d* to support the machine is arranged between the sides below the level of the top and adapted for drawing outwardly upon supports *e* when it is adapted to carry the machine in a position for use. The rear end 45 of this shelf or support has trunnion like projections or pins *f* adapted to slide up or down in slots or grooves *g* in the sides of the cabinet so that if the shelf is raised at the front end and pushed rearwardly its rearward end travels down the guides until the shelf is inclined steeply in its supports,

see Fig. 5. When raised to a horizontal position the trunnion pins *f* may be drawn forwardly into a recess such as *h* in advance of the guide slot so as to provide a 60 rigid support.

Above the space in which the shelf *d* works the table top is open and a leaf portion *j* is employed to close into this space as the shelf is closed in. For this purpose 65 the leaf is swung substantially perpendicular against the fixed portion of the top with part of the leaf within the cabinet and part projecting above it. The leaf may be swung from pivots near the shelf guide by 70 arms or cranks *k* secured to the leaf. The leaf is connected by a cable or cables, or chain or chains *l*, *m*, with the shelf *d* both above and below the level of the shelf, the cables being arranged over pulleys or guides *n*, 75 so that as the shelf is pushed downward the upper part of the table leaf is pulled forwardly and downward on its pivots. By this means the leaf is brought down to close the top of the cabinet and if a 80 hinged front piece *o* is provided on the leaf this may be closed down to occupy the space at the front above the front edge of the shelf and may be locked there. Receptacles for paper and other supplies may 85 be provided on the leaf cover *j* as at *p*.

By this means if the machine is screwed or otherwise secured to its shelf or support *d* as this is lowered into the cabinet the top or leaf is lowered and a closed cabinet 90 for the machine is formed with a flat table top which is useful for other purposes.

By lifting the hinged closure piece on the leaf and drawing the shelf *d* upward and forward the machine is brought up 95 into a position for use, and the table leaf is swung back to leave a clear space above the machine. The rear part of the leaf portion *j* may be weighted to facilitate the operation of the device.

100 Any suitable catch may be provided on the side edge or edges of the shelf portion *d* such as a spring tongue or blade *q*, Fig. 3, to snap out into a recess or the like in the sides of the cabinet and prevent accidental lifting up of the front edge of the shelf when it is in the position shown at Figs. 3 and 4.

I claim:—

110 1. In a typewriter and like table, cabinet sides and a back portion of a tiltable shelf, and a hinged cover and top, said shelf being

adapted for sliding on a support at its front end, said support comprising projecting portions on the cabinet sides, and said shelf further having projecting pins at its rear end, means such as grooves in the cabinet sides to receive and guide said pins of said shelf, means for mounting said cover and top, said means comprising supporting arms rigidly attached to said cover at the sides thereof, said arms being at right angles to said cover and mounted on fixed pivots secured to said cabinet sides, and means such as chains connecting said tilttable shelf and said cover and top so that they may work simultaneously. 5

3. In a typewriter and like table the combination with cabinet sides and a back portion of a tilttable shelf and a hinged cover and top, said shelf being adapted for sliding on a support at its front end, said support comprising projecting portions on the cabinet sides, and said shelf further having projecting pins at its rear end, means such as grooves in the cabinet sides to receive and guide said pins of said shelf, and substantially right angle and forwardly directed extensions of said grooves in which said pins are drawn as the shelf is brought into its horizontal position on its front end supports; recesses in said extensions of said grooves into which said pins engage, with means for mounting said cover and top, said 10 means comprising rigid arms attached to said cover, said arms being at right angles to said cover and mounted on pivots secured to said cabinet sides, and means such as chains connecting said tilttable shelf and said cover and top so that they may work simultaneously. 15

2. In a typewriter and like table, the combination with cabinet sides and a back portion of a tilttable shelf and a hinged cover and top, said shelf being adapted for sliding on a support at its front end, said support comprising projecting portions on the cabinet sides, and said shelf further having projecting pins at its rear end, means such as grooves in the cabinet sides to receive and guide said pins of said shelf, and substantially right angle and forwardly directed extensions of said grooves in which said pins are drawn as the shelf is brought into its horizontal position on its front end supports; recesses in said extensions of said grooves into which said pins engage, with means for mounting said cover and top, said 20 means comprising rigid arms attached to said cover, said arms being at right angles to said cover and mounted on pivots secured to said cabinet sides, and means such as chains connecting said tilttable shelf and said cover and top so that they may work simultaneously. 25

3. In a typewriter and like table the combination with cabinet sides and a back portion of a tilttable shelf and a hinged cover and top, said shelf being adapted for sliding on a support at its front end, said support comprising projecting portions on the cabinet sides, and said shelf further having projecting pins at its rear end, means such as grooves in the cabinet sides to receive and guide said pins of said shelf, and substantially right angle and forwardly directed extensions of said grooves in which said pins are drawn as the shelf is brought into its horizontal position on its front end supports; recesses in said extensions of said grooves into which said pins engage, with means for mounting said cover and top, said 30 means comprising rigid arms attached to said cover, said arms being at right angles to said cover and mounted on pivots secured to said cabinet sides, and means such as chains connecting said tilttable shelf and said cover and top so that they may work simultaneously. 35

In testimony whereof I affix my signature.

JOSEPH ARTHUR JONES
